US0D1091240S

(12) **United States Design Patent** (10) **Patent No.:** **US D1,091,240 S**
(45) **Date of Patent:** **** Sep. 2, 2025**

(54) **COMBINED FOOD SLICER AND SHREDDER**

(71) Applicant: **Shenzhen ZiCheng LanShan Technology Co., Ltd**, Shenzhen (CN)

(72) Inventor: **Yanliang Liu**, Shenzhen (CN)

(73) Assignee: **Shenzhen ZiCheng LanShan Technology Co., Ltd**, Shenzhen (CN)

(**) Term: **15 Years**

(21) Appl. No.: **29/880,979**

(22) Filed: **Jul. 30, 2023**

(51) LOC (15) Cl. **31-00**

(52) U.S. Cl.

USPC **D7/412**; D7/381

(57) **CLAIM**

The ornamental design for a combined food slicer and shredder, as shown and described.

DESCRIPTION

FIG. 1 is a front perspective view of a combined food slicer and shredder, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the combined food slicer and shredder, which form no part of the claimed design.

1 Claim, 8 Drawing Sheets
